SIGNORS TO INSLEY MANUFACTURING COMPANY, OF INDIANAPOLIS, INDIANA, A
CORPORATION OF INDIANA.

DUMPING BUCKET.

1,425,383.

Specification of Letters Patent. Patented Aug. 8, 1922.

Application filed June 21, 1920. Serial No. 390,356.

To all whom it may concern:

Be it known that we, WILLIAM H. INSLEY and ALVIN C. RASMUSSEN, citizens of the United States, residing at Indianapolis, in 5 the county of Marion and State of Indiana, have invented a new and useful Dumping Bucket, of which the following is a specification.

In dumping buckets of that type which 10 is equipped with a downwardly-swinging bottom, difficulty is experienced in releasing the bottom to discharge the load, because, when the full weight of the load becomes impressed upon the operating or 15 controlling lever, said lever is apt to be jerked from the hands of the operator.

The object of our invention is to provide 20 a controlling means for the downwardly-swinging door, or doors, of such dumping bucket, of such character that the operating lever will be very close to the end of its possible movement before the load within the bucket can act upon the released door, or doors.

25 The accompanying drawings illustrate our invention. Fig. 1 is an end elevation in partial vertical section, of a bucket equipped with our improvements and with the dumping doors in closed position; Fig. 2 is a side elevation of the parts shown in Fig. 1 and in a plane at right angles to the plane of Fig. 1; Fig. 3 a view similar to Fig. 1, showing the parts in release position.

In the drawings, 10 indicates an open- 30 bottomed bucket of desired form, provided at its bottom with two hinged bottom-closing doors 11, 11, supported by bridle chains 12, 12, which are connected to chain 13, passed upwardly and downwardly over a 35 pulley 14 and attached at its outer end to the upper end of a goose-neck lever 15, which is pivoted on pin 16 to a link 17 pivoted at 18 upon suitable brackets 19 se- 40 cured to the side of the bucket 10, the goose-neck 15 and link 17 forming a self-locking toggle, as clearly indicated in Fig. 1.

Link 17 is provided with a short arm 45 19 having a projecting pin 20 arranged to be engaged by the operating lever 21, which 50 is pivoted on pin 18. Lever 21 may be locked in place by a removable pin 22 passed through brackets 23 and into lever 21.

The operation is as follows: With the 55 parts in the position shown in Fig. 3, a downward movement of the upper end of le-

ver 21 acting through pin 16, swings link 17 downwardly to the position shown in Fig. 1, this movement drawing the goose-neck 15 and the outer end of chain 13 downwardly, so as to close the doors 11, lever 21 60 serving to swing links 17 far enough to carry the pivot point 16 slightly beyond and inside the vertical plane of the axis of pin 18, thereby automatically locking the toggle 15—17 in place and holding the doors 11 65 against downward displacement under the action of the load within the bucket. When it is desired to dump a load within bucket 10, lever 21 is released and swung upwardly. This upward movement for a major portion 70 thereof is entirely free and independent of the toggle 15—17, but when lever 21 has reached a point distant from its ultimate upper position, lacking an angle approximately equal to that required to swing link 17 75 enough to carry pin 16 outside the vertical plane of the axis of pin 18, lever 19 engages pin 20 and swings it enough to carry pin 16 outside the vertical plane of pin 18, where- 80 upon, the load within the bucket, acting upon the doors 11, opens them suddenly and the toggle 15—17 swings suddenly to the position shown in Fig. 3, but this sudden movement is entirely independent of the manipulating lever 21 because said lever 85 has already reached its upper position.

We claim as our invention:

1. The combination with a bucket having a discharge opening and a closure therefor movable in the direction of opening under the action of the supported load, of a support for said closure, comprising a pair of pivotally-connected links, one connected to the bucket and the other to the closure, a shiftable operating member arranged for movement independent of said links, said operating member and links having inter-engaging portions limiting the independent movement of the operating member at opposite ends of such independent movement, substantially as described.

2. The combination with a bucket having a discharge opening and a closure therefor movable in the direction of opening under the action of the supported load, of a support for said closure comprising a shiftable member connected with the closure, and a manipulating member associated with said shiftable member to move the same to and from closure-sustaining position, said manip-

ulating member being movable independently of the shiftable member through the major portion of its releasing position.

3. The combination with a bucket having
5 a discharge opening and a closure therefor
movable in the direction of opening under
the action of the supported load, of a sup-
port for said closure comprising a cable
attached to the closure, a pair of pivotally-
10 connected links, one pivoted to the bucket
and the other to the cable and arranged to
permit the pivotal connection to be shifted
to either side of the plane of the pivotal

support on the bucket relative to the line
of the cable, and a manipulating lever piv- 15
oted upon the bucket and having two one-
way interengagements with one of the links,
substantially as and for the purpose set
forth.

In witness whereof we have hereunto 20
set our hands at Indianapolis, Indiana, this
8th day of June, A. D. one thousand nine
hundred and twenty.

WILLIAM H. INSLEY.
ALVIN C. RASMUSSEN.
